UNITED STATES PATENT OFFICE.

EDWIN HENRY COLPITTS, OF EAST ORANGE, NEW JERSEY, ASSIGNOR TO WESTERN ELECTRIC COMPANY, OF NEW YORK, N. Y., A CORPORATION OF ILLINOIS.

CONNECTING-CIRCUIT FOR MAGNETO TELEPHONE-EXCHANGE SYSTEMS.

1,029,593.

Specification of Letters Patent.

Patented June 18, 1912.

Application filed September 15, 1910. Serial No. 582,248.

To all whom it may concern:

Be it known that I, EDWIN H. COLPITTS, subject of the King of Great Britain, residing at East Orange, in the county of 5 Essex and State of New Jersey, have invented a certain new and useful Improvement in Connecting-Circuits for Magneto Telephone-Exchange Systems, of which the following is a full, clear, concise, and exact 10 description.

This invention concerns signaling means employed in telephone exchange systems of the magneto type. Its object is to provide a connecting circuit of high transmission efficiency employing a common clearing-out signal for a pair of connected subscribers. Although such a system enables a reduction in the amount of apparatus involved, these systems as heretofore equipped have been 15 open to the objection that one subscriber in actuating his magneto to give the disconnect signal frequently rings through the connecting circuit and operates the bell of the line of the subscriber with whom he has 20 been talking or causes disagreeable noises in his telephone, according to the condition of such subscriber's substation apparatus at the moment. This objectionable secondary current is in one type of connecting circuit 25 due to the mutual inductance of the windings of the repeating coil and that of the windings of the clearing-out signal, induced current being created in the secondaries of each of these devices upon the flow 30 of ringing current through their primaries which currents are cumulative, or in another type wherein the repeating coil is not present in the circuit, the objectionable secondary current is that created by the mutual 35 inductance of the clearing-out signal alone. Another common defect in such systems is that the low resistance bridge across the line caused by either connected subscriber's instruments being included in circuit at the 40 time the disconnect signal is sent out from the other connected line exerts a shunting effect on the high resistance clearing-out signal, frequently preventing its operation.

The present invention eliminates the first 45 objection by taking advantage of the principle that electro-motive forces of equal strength and opposite direction created in a circuit neutralize each other, thereby pre-

venting any flow of current, and eliminates the second by conductively separating the 55 connecting circuit.

Since currents of two characters differing radically in frequency are employed, one for signaling and the other for talking, the above stated principle is utilized in the following manner to accomplish the desired results. The connecting circuit may be divided into a plurality of sections united by induction coils, one of which is arranged to operate a clearing-out signal, these induction coils being so constructed and arranged in the respective sections that upon the passage of ringing current through either section electromotive forces are induced in the secondary section which oppose each other 60 and thus prevent an appreciable current flow, means being associated with said sections to permit of the unaltered reproduction in one section of telephonic currents circulating in the other. Preferably the 65 connecting circuit is split into two sections united inductively through a repeating coil and a clearing-out signal, each section leading in series through a winding of each induction coil, the relation of the direction of 70 the winding of one induction coil in one section to the direction of the winding of the other in the same section being opposite to that existing between the windings 75 of the respective induction coils in the other section. Or, to state the same thing in different language, the inductive relation between the windings of the repeating coil is 80 opposite to that between the windings of the clearing-out signal. It will be apparent 85 therefore that the electromotive force induced in the secondary winding in either induction coil due to the flow of ringing current in its primary, is opposite to that induced in the secondary of the other induction coil, 90 thus preventing an appreciable current flow in the secondary section and thereby in the second subscriber's line. The unaltered reproduction in the secondary section and thereby in the substation connected therewith of the telephonic currents circulating 95 in the primary section is preferably provided for by bridging condensers around the respective windings of the clearing-out signal.

The accompanying drawing is a diagram-

matic illustration of a telephone system equipped with a cord circuit of my invention.

The substations 1, 2 terminate at the central office in the usual springjacks J, J' respectively, and include apparatus that is too well known to require description.

The cord circuit C is in two sections inductively related at their inner ends and 10 each terminating at its outer end in a plug P, P' by means of which connection with substations 1, 2 respectively is established. While the repeating coil R is shown with four windings r, r', r^2, r^3 , we shall consider 15 for convenience of description r and r' as one winding and r^2, r^3 as another; it being understood of course that the illustration of the repeating coil is purely diagrammatic. The repeating coil R, as is well understood, 20 reproduces in either section voice currents circulating in the other, the winding r, r' being connected in series with plug P and the winding r^2, r^3 in series with plug P'. A clearing-out signal, which may be an annunciator A, as shown, is provided with a 25 pair of energizing windings, a, a' , one conductively connected with each section of the cord circuit and each in series with the winding of its respective side of the repeating coil, the said annunciator being thereby 30 responsive to signaling current circulating in either section originating at the respective substation. The inductive relation between the drop windings a, a' is opposite to that 35 between the repeating coil windings r, r' considered as one and r^2, r^3 considered as the other. This is indicated in the drawing by showing the windings a, a' of the drop A wound in opposite directions upon their 40 common core and the repeating coil windings arranged as usual. Connected in series with winding r, r' of repeating coil R and in shunt of annunciator winding a is a condenser c . A condenser c' is similarly associated with the other section. The condensers c, c' afford paths around the respective drop windings a, a' for the high frequency telephonic currents, said currents readily taking these paths because of the 45 relatively high impedance of the alternative paths including the drop windings. On the other hand, these condenser paths do not admit of the passage of an appreciable quantity of the low frequency signaling currents, 50 which are thus compelled to traverse the drop windings and thus energize the drop.

By reference to the drawing it will be observed that upon the actuation of either magneto and the consequent passage of signaling current through the corresponding section made up of the repeating coil and annunciator windings in series, the potential across the terminals of the other section of the circuit is not appreciably raised; that 55 is, the electromotive forces induced in the

secondaries of the respective induction devices oppose each other with no appreciable resultant current flow. On the other hand, since, due to the presence of condensers c, c' in shunt of drop windings a, a' respectively, 70 no appreciable amount of primary telephonic current circulates in either drop winding, it follows that practically no induced telephonic currents are created in the secondary drop winding, and consequently 75 telephonic currents circulating in the primary section of the connecting circuit are reproduced unaltered in the secondary section by the repeating coil R and are taken up in turn by the repeating coil of the substation apparatus connected therewith. 80

It is preferable to construct the respective induction coils with approximately equal mutual inductance at ringing frequencies; that is to say, the electromotive force induced in the secondary winding of either device due to the flow of signaling current in its primary should be approximately equal to that induced in the secondary of the other due to the flow of the same current in its primary winding, although it is apparent that to secure the desired result it is only necessary that the induced electromotive forces should be divided into approximately equal component parts which 90 oppose each other, and that one induction coil need not be of equal inductance with the other providing it be associated with other means for raising or lowering its inductance to the required amount. 100

It will of course be understood that the term "direction of winding" used throughout the specification and claims really means the direction of the current flow, annunciators in practice being wound similarly to repeating coils, the method of connecting the windings in the circuit determining the direction of current flow and thereby their inductive effect. 105

It is not intended that the invention be limited to the embodiment shown, since the desired result may be secured by connecting the necessary induction and capacity instrumentalities in the connecting circuit in a variety of ways. 110

I claim:—

1. A connecting circuit in a plurality of sections, induction coils having their primaries connected in series in one section and their secondaries connected in series in another, the relation of the direction of winding of one secondary to the other being opposite to that between the primaries, and shunt paths for telephonic current around the respective windings of one induction coil, said paths offering comparatively high resistance to the ringing current. 120

2. A connecting circuit in a plurality of sections, a pair of induction coils with their corresponding windings in each section se- 125

rially connected together, the inductive relation between the windings of the respective devices being opposite, thereby creating upon the passage of ringing current 5 through the primary section electromotive forces of opposite polarity in the secondary section, and means for shunting telephonic current around the respective windings of one induction coil, said means offering comparatively high resistance to the ringing current.

3. A connecting circuit comprising sections united through a plurality of induction coils having their corresponding windings 15 in each section connected together and in such a manner that due to their inductive relation the passage of ringing current through the primary section creates electromotive forces of opposite polarity in the secondary section, and condensers for shunting telephonic current around the respective windings of one induction coil.

4. A connecting circuit in two sections united inductively through two induction 25 coils, each section leading through corresponding windings of the respective induction coils in each section in series, the relation of the direction of winding of one induction coil in one section to the winding 30 of the other induction coil in the same section being opposite to that between the windings of the induction coils in the other section, means for impressing ringing and telephonic currents upon each section, said 35 ringing current traversing a winding of each induction coil in each section, a signal actuated upon the flow of said ringing current, and condensers for shunting said telephonic current around the windings of one induction 40 coil in both sections.

5. A connecting circuit in two sections united through a repeating coil and annunciator, each section leading through corresponding windings of each induction coil in 45 each section in series, the relation of the direction of winding of one induction coil in one section to the winding of the other in

the same section being opposite to that between the windings of the induction coils of the other section, and a condenser in parallel with each annunciator winding in the respective sections.

6. A connecting circuit consisting of two sections each leading serially through windings of a repeating coil and annunciator, the 50 respective mutual inductances of said devices being approximately equal at ringing frequencies, and the annunciator windings being connected to have an inductive relation opposite to the repeating coil windings, 55 and a condenser in a divided circuit with each annunciator winding, whereby ringing current circulating in either section induces in the other electromotive forces approximately equal and opposite, while telephonic 60 currents circulating in either repeating coil winding reproduce themselves in the other and are afforded a path around the corresponding annunciator winding through its 65 associated condenser.

7. In a telephone exchange system, the combination with a connecting circuit in two sections, a repeating coil and an annunciator uniting said sections inductively, telephonic apparatus and means for generating ringing current connected with each section, the arrangement of the windings of said repeating coil and annunciator being such that the ringing currents induced in the secondary section are approximately equal in strength 70 and opposite in direction, and means for so altering the exterminative effect of said windings upon the flow of telephonic current as to permit of the unaltered reproduction or transfer of such current from 75 either section to the other.

In witness whereof, I, hereunto subscribe my name this 14th day of September A. D., 1910.

EDWIN HENRY COLPITTS.
